(57) **CLAIM**

The ornamental design for the “net”, as shown and described.

DESCRIPTION

FIG. 1 is a front perspective view of a net showing my new design, the frame shown in broken lines for illustrative purposes only and forms no part of the claimed design; FIG. 2 is a front elevational view of a second embodiment of FIG. 1;

FIG. 3 is a side view of the net on a larger scale, the net partially broken away for ease of illustration and the frame shown in broken lines for illustrative purposes only and forms no part of the claimed design;

FIG. 4 is a perspective view of FIG. 3;

FIG. 5 is a front view of FIG. 1, the net partially broken away for ease of illustration and the frame and hockey puck shown in broken lines for illustrative purposes only and forms no part of the claimed design;

FIG. 6 is a cross-sectional view of FIG. 5, showing the net in use; and,

FIG. 7 is a cross-sectional view of FIG. 5, showing the net in use.

1 Claim, 2 Drawing Sheets

FIG. 2

FIG. 1
